(57) **CLAIM**

I claim the ornamental design for a semi-con scoring tool, as shown and described.

DESCRIPTION

FIG. 1 is a front right top perspective view of a semi-con scoring tool design according to my invention;

FIG. 2 is a back right top perspective view of the semi-con scoring tool design shown in FIG. 1;

FIG. 3 is a front right bottom perspective view of the semi-con scoring tool shown in FIG. 1;

FIG. 4 is a back right bottom perspective view of the semi-con scoring tool shown in FIG. 1;

FIG. 5 is a front elevational view of the semi-con scoring tool shown in FIG. 1;

FIG. 6 is a back elevational view of the semi-con scoring tool shown in FIG. 1;

FIG. 7 is a top elevational view of the semi-con scoring tool shown in FIG. 1;

FIG. 8 is a right elevational view of the semi-con scoring tool shown in FIG. 1;

FIG. 9 is a left elevational view of the semi-con scoring tool shown in FIG. 1;

FIG. 10 is a bottom elevational view of the semi-con scoring tool shown in FIG. 1;

FIG. 11 is a back left top perspective view of the semi-con scoring tool shown in FIG. 1; and,

FIG. 12 is a front left top perspective view of the semi-con scoring tool shown in FIG. 1.

The solid black surface shading in FIGS. 1-6, 8, 9, 11 and 12 indicated a feature of the semi-con scoring tool showing color contrast.
